UNITED STATES PATENT OFFICE

GEORGE D. WILSON, OF BERKELEY, CALIFORNIA, ASSIGNOR TO AMERICAN METER COMPANY, INC., OF NEW YORK, N. Y., A CORPORATION OF DELAWARE

CRANK-SHAFT ASSEMBLY

Application filed January 18, 1928. Serial No. 247,692.

This invention relates to improvements in meter boxes, and more particularly to the mounting of the crank shaft and the construction of the crank portion of the shaft which operates the valve covers.

5 The shaft construction and mounting as heretofore practiced in meter boxes provided a crank having two points of bearing, one above the crank portion and one below, that 10 above consisting of the stuffing box in the angle piece, and the one below consisting of the boot within which the end of the crank operates.

This construction necessitated a crank having two shaft portions in axial alignment, and the offset crank lying therebetween, which construction was difficult to manufacture and required extreme exactness in the operation of forming the parts. The mounting of such 20 shaft set up a condition, when any shifting of the stuffing box or boot would occur, there would likely be a bind of the shaft, either in the stuffing box or the boot, which would interfere with the free rotation of the shaft, 25 causing faulty operation and inaccurate registering of the meter.

By my present invention, I suspend the shaft in a single bearing, and thus insure the free rotation of the same. I also provide an 30 accurately formed and cheaply constructed crank portion for the shaft, adapted for manufacture without bending the main portion of the shaft proper.

With the above mentioned and other objects in view, the invention consists in the novel construction and combination of parts hereinafter described, illustrated in the accompanying drawings and pointed out in the claim hereto appended; it being understood 40 that various changes in the form, proportion, size and minor details of construction within the scope of the claim may be resorted to without departing from the spirit or sacrificing any of the advantages of the invention.

To more fully comprehend the invention, reference is directed to the accompanying drawings, wherein—

50 Fig. 1 is a view in top plan of a portion of

a meter box with my invention applied thereto.

Fig. 2 is a vertical sectional view on line 2—2 Fig. 1.

Fig. 3 is a view in top plan of a meter box 55 with one outer wall removed, and

Fig. 4 is a view in vertical section of the crank, crank shaft and crank pin.

In the drawings, wherein like characters designate corresponding parts, 1 is a meter box, Fig. 3, with one wall removed, disclosing the inner wall 2, commonly termed a table. The space within the box 1 between the table 2 and the removed wall, provides a chamber 3, which is divided by the wall 4, rectangular in plan, the latter forming the valve and mechanism chamber 5 which is closed by a back plate 6, sealing the area between the walls 7, 8 and 9 and the upper surface of the wall 4, Figs. 1 and 2.

70 In the angle of the wall 4 is placed an angle piece or plate 10, supporting stuffing box 11, extending at right angles therethrough. The surface of the plate 10 mounts a king post 12 having an angular bend 13, formed with a bearing recess overlying the stuffing box 11.

75 Rotatable within the stuffing box 11, extending above and below the same, with its upper end received in the bearing recess in 80 the angular bend 13, is a crank shaft 14, the lower end of which is reduced at 15, forming a shoulder 16 and having an axial recess 15^a in its reduced end to form a relatively thin and readily swaged wall.

85 17 indicates a crank plate formed at its opposite ends with apertures 18 and 19. Through the aperture 18 extends the reduced portion 15 of the shaft 14, with the surface of the crank plate 17 resting against the shoulder 16. In this position, the projecting reduced end of the shaft 14 is swaged at 20, tightly securing the crank plate 17 to the shaft 14, with the plate extending at right angles from the shaft, as in Fig. 4.

90 Upwardly through the aperture 19, in the crank 17, extends the reduced upper end 21 of crank pin 22, with the under-surface of the plate 17 engaging with the shoulder 23 on the pin 22 said pin having an axial recess 100

22 in its reduced end to form a relatively thin and readily swaged wall.

When thus positioned, the upper end of pin 22 is swaged at 24 to tightly secure the same to the outer end of the plate 17.

5 Transversely through the lower end of the pin 22 extends a pin bore 25, in which is mounted a locking key 26, the latter holding valve arms 27 in position in the crank pin 22.

10 The valve arms 27 are of conventional form and are pivotally connected to valve covers 28, which are reciprocally associated with the respective valve seats 29.

It will be observed that any shifting between the table and angle piece will not, in any manner, interfere with the free rotation of the shaft 14, and it will also be observed that by constructing the crank plate 17 and pin 22 of assembled parts, the liability of throwing the main portion of the shaft 14 out of alignment, which often took place during the previous crank bending operations, is entirely overcome.

I claim:—

25 A crank shaft assembly for operatively mounting the pitmen of valves for meter boxes, comprising a shaft provided with a reduced end portion so as to form a shoulder, said reduced end portion being axially recessed so as to provide a bendable wall, a crank plate provided with a pair of apertures, said plate of lesser thickness than the axial length of the reduced portion of the shaft and being snugly fitted thereover to extend laterally therefrom with the reduced portion of the shaft in position through one aperture, a crank pin provided with a reduced end portion constructed similar to the reduced end portion of the shaft and extended through 35 the other of the apertures in said plate in a direction reverse to the direction of extension of the shaft, the reduced portions of said shaft and crank pin made operatively integral and resistably with said crank plate by 40 being swaged respectively thereto, said crank pin provided with a cylindrical axially aligned body having a transverse opening therethrough adjacent its free end and adapted to receive and releasably hold a locking 45 key, the said crank shaft assembly being 50 mounted rotatably by a bearing engagement of the shaft and having its crank and crank pin portions free of bearing.

In testimony whereof I have signed my name to this specification.

GEORGE D. WILSON.
